UNITED STATES PATENT OFFICE.

WILLIAM J. BURKART, OF PITTSBURGH, PENNSYLVANIA, ASSIGNOR TO PITTSBURGH ENGINEERING COMPANY, A CORPORATION OF PENNSYLVANIA.

AIR-ELIMINATOR.

1,247,218.

Specification of Letters Patent. Patented Nov. 20, 1917.

Application filed November 20, 1916. Serial No. 132,447.

To all whom it may concern:

Be it known that I, WILLIAM J. BURKART, a resident of Pittsburgh, in the county of Allegheny and State of Pennsylvania, have invented a new and useful Improvement in Air-Eliminators, of which the following is a specification.

This invention relates to air eliminators for steam lines, and particularly for heating systems.

The objects of the invention include ready escape of air from a steam circulation system at a point in the return line; the prevention of the escape of water and steam; and mechanism for controlling the air passage for these purposes of simple construction and positive operation. Another object of the invention is to provide means to prevent the drawing of air into the pipes through the escape port; and this is done by a float sealed device.

The various uses and advantages of the invention will be more fully set forth in the following specification, illustrated by the accompanying drawings, wherein an elevation of the apparatus is shown, the movable parts and their casings being shown in section.

Air eliminators are in use having in view the same general objects as here, but the construction has been different, and have had defects in operation which have been eliminated in the present case.

In a system of heating by steam, a boiler is connected to a line which leads through the various rooms and radiating units to be heated and then returns to the boiler. In various ways air gets into the circulation, and it is important that this be eliminated. A part of the steam is condensed in the line and radiators, and the water so formed is forced back into the boiler and so used again. The steam that returns is also valuable and must not be allowed to escape through the air eliminator. Therefore the problem is to permit ready expulsion of air through a device locked against passage of steam or water. There is a further problem in that air must not be allowed to pass into the system by reverse flow through the air eliminator; and this must be positively guarded against, since a sudden chilling of the radiators causes a large amount of steam to condense and so creates a partial vacuum in the line, which would draw air through

the escape port if no means of prevention were provided.

All of these functions are found in the present invention, which comprises a return line 1 having a T-connection to a pipe 2 leading downward to the lower port of a boiler in the circulating system and a pipe 3 leading upward to the air eliminating apparatus. This consists of a casing 4 having an opening 5 to the pipe 3, and an opening 6 at its top to a second casing 7. In the casing 4 a large float 8 is mounted on a lower stem 9 and upper stem 10; the lower stem passing through an opening in the lower wall of the casing and so acting as a guide for the vertical movement of the float. A collar is fixed on stem 9 and seats on the lower wall of the casing 4 to limit the downward travel of the float, as will be obvious. The upper stem 10 is similarly guided by an opening in the upper part of the casing, here shown as a reentrant supplementary wall 12, forming a small chamber 13, connected to the main chamber 14 by ports 6, above mentioned.

The supplementary wall 12 is continued upward beyond the top of the main casing 4, and is internally threaded to engage the supplementary casing 7, the lower end of which is beveled to form a valve seat 15. On the upper end of stem 10, inside chamber 13, a valve disk 16 is fixed, adapted when the float is raised to coöperate with seat 15 to close the passage 17 between casings 4 and 7.

Another beveled valve seat 18 is provided in the casing 7 at the upper end of passage 17. The chamber 19, formed by casing 7, is closed by a threaded member 20, having free ports 21 therethrough, and carrying a thermostat member 22, inside chamber 19. This thermostat consists of a stem, in two parts, one being fixed to the casing wall, the other carrying a valve disk 23 adapted to coöperate with seat 18 to close the passage 17, when a volatile liquid contained in drums 24 expands to lengthen the stem of the thermostat member. This thermostat is not itself new; its operation is well known; and no extended description is here necessary.

A pipe 25 leads upward from casing 7 and then down to another casing 26, from which a port or pipe 27 leads to the atmosphere. The pipe 25 is threaded through the

top of casing 26, and in the chamber 28, formed by said casing, carries a bell-shaped open terminal 29, ending below the pipe 27. The casing 26 is closed by a threaded member 30, to make the chamber 28 fluid tight at the bottom, and it is filled with water to the height of pipe 27. A float 31, in the form of a hollow sphere, of any suitable material, is held in the mouth of bell-shaped terminal 29 by its buoyancy in the water.

The operation is as follows: Steam generated in a boiler (not shown) passes through the heating and radiating system (not shown) and then returns by pipes 1 and 2 to the boiler. A certain amount of water of condensation and of air are mixed with steam in the return line. The water, of course, flows down pipe 2, and collects in that pipe, which connects by a non-return valve to the feed supply of the boiler. When pressure in the system mounts high enough to equalize (or nearly equalize) the pressure above this water and the boiler pressure, it passes into the feed supply and is used again to make steam.

Air in the return pipe will rise in pipe 3, pass freely through chamber 14, passage 17, chamber 19, pipe 25, depress the ball-float 31 and out the pipe 27 to the atmosphere.

Should a large amount of water come through pipe 1 so as to back up into chamber 14, the float 8 will rise, seating valve disk 16 and closing passage 17 against escape of water. Pressure will eventually build up and the water be forced out to the boiler.

Should steam come through the return pipe to the eliminator, it will rise through chamber 14 and into chamber 19, enveloping the thermostat therein. The steam is of course at a temperature above 212 degrees Fahrenheit, and the thermostat is so made that such temperature will expand it suffi-

ciently to seat the valve disk 23, and so close the passage 17 against escape of steam. 45

Sometimes a sudden chilling of the radiators condenses a large amount of steam and creates a partial vacuum in the system. In such case air cannot reenter by the eliminator, even though both valves 16 and 23 be unseated, because the ball float 31 is always in position to close the mouth-piece 29 against any upward flow therein, and the greater the pressure, the tighter this closure.

It will be observed by those familiar with the art that the float 8 is of large size, is accurately guided and mounted so that it cannot stick or get out of position; that the float 31 is not attached to any part and cannot be displaced or stick, and that the whole apparatus is simple and positive in operation. The thermostat is ordinarily mounted so as to be adjustable with relation to the valve seat, though this is not here shown. 60

I claim:—

In a steam heating system comprising a return line, an air eliminator comprising a casing connected to the return line, a float in the casing having a guiding stem and a valve thereon adapted to close a passage 70 from the casing, a thermostatically controlled valve also controlling the passage from the casing, and a pipe extending downward from the passage through the casing having a bell-shaped terminal, a casing 75 surrounding the terminal, a ball float in said casing adapted to seat against the terminal and form a non-return valve, and a lateral passage from the casing above the level of the terminal. 80

In testimony whereof, I have hereunto set my hand.

WILLIAM J. BURKART.
